UNITED STATES PATENT OFFICE.

CARL RUSH, OF WHARTON, TEXAS.

WASHBOARD.

1,412,710.

Specification of Letters Patent. Patented Apr. 11, 1922.

Application filed June 29, 1917. Serial No. 177,803.

To all whom it may concern:

Be it known that I, CARL RUSH, a citizen of the United States, residing at Wharton, in the county of Wharton and State of Texas, have invented certain new and useful Improvements in Washboards; and I do hereby declare the following to be a full, clear, and exact description of the invention, such as will enable others skilled in the art to which it appertains to make and use the same.

This invention relates to improvements in washboards.

The object of this invention is to provide a washboard which will effect a rapid cleansing of the clothes with a light rubbing, thus saving time, labor and unnecessary wear upon the goods being washed.

A still further object of this invention is to provide a washboard which will be inexpensive in construction, light and durable and can be manufactured and sold at a low cost.

With these and other objects in view the invention consists in the novel combination, and arrangement of parts hereinafter more fully described and set forth in the claims hereto appended.

In the drawings,

Figure 1 is a front elevation of a washboard made in accordance with this invention,

Figure 2 is a rear elevation of the same,

Figure 3 is a vertical sectional view partly broken away,

Figure 4 is a fragmentary transverse sectional view, and

Figure 5 is a vertical sectional view of the upper portion of the board.

Like numerals of reference designate corresponding parts in all the figures of the drawing.

Referring to the drawing, the numerals 1 and 2 designate the legs of the washboard, each of which is provided on its inner face with a longitudinally extending groove 3. The upper ends of the legs are connected together by the transverse head board 4 which extends laterally beyond the exterior of each of the legs thereof. A transverse supporting block 5 is secured to the opposing faces of the legs 1 and 2 respectively in rear of the longitudinal grooves 3 and adjacent the upper ends thereof. A transverse supporting brace 6 is secured to the opposing faces of the legs 1 and 2 respectively adjacent the lower ends thereof and in rear of the grooves

3 and in spaced relation to the block 5. A vertical brace 7 is secured to the opposing faces of the braces 5 and 6 respectively centrally of their ends and constitutes the back 60 of the board when assembled.

A corrugated zinc plate 8 has its opposite side edges fitted in the grooves 3 in the opposing faces of each of the legs 1 and 2 respectively. A straight vertical portion of 65 the corrugated plate is secured to the forward face of the block 5, as at 9, an adjoining straight horizontal portion secured upon the upper side of the block 5, as at 10, and the plate then extended upwardly, as at 11, 70 offset as at 12, and the upper end 13 thereof secured to the rear surface of the head block 4, the portion 11 of the upper end of the corrugated zinc plate constitutes a soap receiving compartment 14 on the front face of the 75 drawing.

It will be noted that parts 10 and 12 form shoulder portions which are disposed intermediate and in contact with the transverse 80 frame members 4 and 5 to resist longitudinal displacement of the plate or scrubbing member 8.

The lower end of the corrugated plate extends downwardly and is secured to the front 85 side of the reinforcing block 6 as at 15 having its terminal bent inwardly and secured to the under side of the block 6 as at 16 thus rigidly positioning and securing the corrugated zinc plate between the opposing faces 90 of the legs 1 and 2 respectively and to the blocks 5 and 6 of the board.

A pair of transversely arranged reinforcing straps 17 are secured as at 18 to the rear surfaces of the legs 1 and 2 respectively and 95 to the lower supporting block 6 as at 19. These straps may be constructed of metal or any other material suitable for the purpose. A pair of reinforcing straps 21 are secured in a vertical plane to the legs 1 and 2 and have their upper ends extended laterally and secured to the block 5 as at 22 to reinforce the upper portion of the board as illustrated in Figure 2 of the drawing.

What is claimed is:—

A washboard having legs, spaced transverse frame members connecting the legs, a scrubbing member in a single piece having a scrubbing portion and an offset shoulder portion extending from the scrubbing portion, 110 said legs having grooves to receive the side edges of the scrubbing portion, a back ex-

tending from the shoulder portion in the opposite direction to the scrubbing portion, a shoulder portion extending from the back in the opposite direction to the first mentioned shoulder portion, said shoulder portions being disposed between and in contact with said transverse frame members to resist longitudinal displacement of the scrubbing member, a securing portion extending from 10 the second mentioned shoulder portion in the opposite direction to said back, said legs, back and shoulder portions cooperating to

provide a soap compartment, a third transverse frame member, and said scrubbing member having an offset flange extending in 15 the same direction as the first mentioned shoulder portion and overlapping said third transverse frame member.

In testimony whereof I affix my signature in presence of two witnesses.

CARL RUSH.
